DESIGN FOR A CIGARETTE PACK HOLDER

Edward Kanter, Cleveland Heights, Ohio

Application July 14, 1941, Serial No. 102,127

Term of patent 3½ years

To all whom it may concern:

Be it known that I, Edward Kanter, a citizen of the United States, residing at Cleveland Heights, county of Cuyahoga and State of Ohio, have invented a new, original, and ornamental Design for a Cigarette Pack Holder, of which the following is a specification, reference being had to the accompanying drawing, forming a part thereof, wherein Fig. 1 is a front perspective view; Fig. 2 is a rear perspective view; and Fig. 3 is a sectional view taken on the line 3—3 of Fig. 1, of a cigarette pack holder, showing my new design.

I claim:

The ornamental design for a cigarette pack holder, substantially as shown.

EDWARD KANTER.
